QUILL DRIVE FOR VERTICAL DRILLING OR MILLING MACHINE

Warren E. Ponemon, Oyster Bay, N.Y., assignor to
Autonumerics, Inc., Westbury, N.Y.

Filed Oct. 4, 1971, Ser. No. 186,585

Term of patent 14 years

Int. Cl. D15—99

U.S. Cl. D54—14 B

FIG. 2

FIG. 3

FIG. 1

FIG. 4

FIG. 1 is a front view of a quill drive for vertical drilling or milling machine showing my new design;

FIG. 2 is a top plan view thereof;

FIG. 3 is a right side elevational view thereof; and

FIG. 4 is a rear view thereof.

The side opposite that shown is substantially the same as the side that is shown.

I claim:

The ornamental design for a quill drive for vertical drilling or milling machine, substantially as shown and described.
